UNITED STATES PATENT OFFICE.

WILLIAM J. McCAIN, OF LIVINGSTON, ALABAMA.

AIR-CIRCULATING FIREBACK.

Application filed June 11, 1928. Serial No. 284,643.

My invention relates to an air circulating fire back for open fire places, employed to utilize more effectively the heat of the fuel burned in the fire place, and has for its object the provision of apparatus of the character designated which shall be simple of design and economical of manufacture and which shall include means whereby the parts thereof subjected to the greatest heat may be readily replaced.

A further object of my invention is to provide an air circulating fire back for open fire places which shall include permanent end manifolds and a replaceable central section directly subjected to the heat of the fire, together with cooperating baffles for effecting a circulation of air through the manifolds and the central section.

Air circulating fire backs, as heretofore known to me, have usually comprised a hollow structure, either set in place in the fire place and unattached to the side walls thereof, or else permanently built into the masonry of the fire place. The first mentioned type eliminates the necessity of making unsightly air conduit connections thereto in the fire place and has accordingly not gone into wide commercial use. Where the fire back is permanently built into the masonry, the central portion which is subjected to the heat of the fuel and the gases of combustion eventually burns out and, in order to replace the burned out portion, it has heretofore been necessary to dismantle the masonry of the fire place and replace the entire structure.

All of the above difficulties are overcome by means of my invention and I have provided a fire back having end manifolds with air inlet and outlet connections permanently built in the masonry of the fire place and a readily replaceable central section fitting into the end manifolds. Cooperating baffles are provided in the end manifolds and in the central section whereby the most effective heat transfer is obtained between the fire and the air being circulated. Furthermore, the passages formed by the baffles in the fire back are of progressively increasing cross sectional areas thereby compensating for the increased volume of the air as it is heated.

Apparatus embodying features of my invention is illustrated in the accompanying

drawings, forming a part of this application, wherein

Fig. 1 is a vertical sectional view along the line I—I of Fig. 2;

Fig. 2 is a sectional plan view along the line II—II of Fig. 1;

Fig. 3 is a sectional view of the fire back removed from the fire place, taken along the line III—III of Fig. 2;

Figs. 4, 5 and 6 show separate elevations of the end manifolds and central replaceable section.

Referring to the drawings for a better understanding of my invention, I show a fire-place having the usual masonry side walls 10 and 11 and back wall 12. Fuel is burned in the fireplace as in a grate 13.

Disposed within the fireplace to the rear of the grate 13 is my improved air circulating fire back which comprises end manifolds 14 and 16 and a central replaceable section 26. Where the fire back is being installed in a house being built, the end manifolds 14 and 16 are built into the masonry of the side walls 10 and 11, thus avoiding unsightly air inlet and outlet connections to the manifold which would necessarily have to be in plain view from the room. Leading to the manifold 14 is an air inlet conduit 18, also built into the masonry and provided with a damper 19 to regulate the flow of air into the fire back. Leading from the upper portion of both of the manifolds 14 and 16 are outlet conduits 21 and 22 which may lead to any room desired to be heated remote from the fireplace. In Fig. 1 of the drawings, the conduit 21 is shown leading to a room at the rear of the fireplace, but this is for the purpose of illustration only and such conduits may be led to any desired place.

Each of the manifolds 14 and 16 is provided with an overhanging flange 23 which extends across the top and bottom thereof and to the rear thereof, but does not extend down the front. Interposed between the manifolds 14 and 16 and resting on the flange 23 is a central air heating section 26 through which the air entering the fire back circulates before its exit from the outlet conduits 21 and 22. Preferably, the flanges of the end manifolds extend just through the permanent masonry of the chimney and the joint be-

tween the central section and the manifolds, at the front, is made tight by a fire brick lining overlapping the joint as shown at 25. When necessary to replace the central section, 5 it is only necessary to remove the fire brick lining, leaving undisturbed the masonry of the chimney.

The central section comprises a front, forwardly inclined plate 27 overhanging the 10 grate 13, a top plate 28, a bottom plate 29 and a back plate 31. The front plate 27 is preferably made of cast iron the better to resist the action of the fire and gases of combustion, while the other plates may be made of any 15 suitable metal. The front plate 27 is provided with longitudinally extending grooves 32 and 33 for the reception of baffles 34 and 36 which are secured to the rear plate 31 in any suitable manner. It will be observed 20 that the arrangement of the baffles is such as to provide transverse passages of progressively increasing cross sectional area for the air being heated.

The manifold 14 is provided with a baffle 25 37 in alignment with the baffle 36 and above the air inlet conduit 18. The manifold 16 is provided with a baffle 38 in alignment with the baffle 34 and beneath the outlet conduit 22 so that air entering the apparatus through 30 the inlet conduit 18 flows beneath the baffles 36 across the fire back, then back across the baffle 34 to the manifold 14 as shown by the arrows. From the manifold 14 the heated air may leave through the outlet conduit 21 35 or flow back across the fire back to the outlet conduit 22. In order to regulate the flow of air through the outlet conduits, they are provided with suitable dampers 41, only one of which is shown.

40 From the foregoing it will be apparent that I have devised an improved air circulating fire back for fire places which is simple of construction and economical of manufacture and wherein means are provided for readily 45 replacing the parts subjected to the heat of the fire and gases of combustion. It will furthermore be apparent that my improved fire back provides for effective heat transfer between the fire and the air being circulated.

50 While I have shown my invention in but one form it will be obvious to those skilled in the art that it is not so limited but is susceptible of various changes and modifications without departing from the spirit thereof and 55 I desire therefore that only such limitations

shall be placed thereupon as are imposed by the prior art or as are specifically set forth in the appended claims.

What I claim is:

1. In an air circulating fire back for fire- 60 places, a manifold at each end of the fire back, air conduits connected to the manifolds, and a removable heat transfer section interposed between the manifolds.

2. In an air circulating fire back for fire- 65 places, a pair of end manifolds remote from the fire, a hollow central removable section subjected to the heat of the fire, air inlet and outlet conduits connected to the manifolds, and cooperating baffles disposed within the 70 end manifolds and the central section providing passages for the transverse flow of air through the fire back to the outlet conduits.

3. In an air circulating fire back for fire- 75 places, a pair of end manifolds remote from the fire, a hollow central removable section subjected to the heat of the fire, a forwardly inclined plate included in the removable section and overhanging the fuel 80 burning portion of the fireplace, an air inlet conduit connected to the lower portion of one of the manifolds, an air outlet conduit connected to the upper portion of one of the manifolds, and cooperating baffles disposed within the end manifolds and the central section providing 85 passages of increasing cross sectional area for the transverse flow of air through the fire back to the outlet conduits.

4. In an air circulating fire back for fire- 90 places, a pair of end manifolds embedded in the side masonry of the fireplace and each having a supporting flange projecting into the fireplace, a hollow removable central section resting on the supporting flanges, a forwardly inclined plate overhanging the fuel 95 burning portion of the fireplace, an air inlet conduit connected to the lower portion of one of the manifolds, an air outlet conduit connected to the upper portion of one of the manifolds and leading to a place to be heated 100 remote from the fireplace, and cooperating baffles disposed within the end manifolds and the central section and arranged to provide 105 passages of increasing cross sectional area for the transverse flow of air through the fire back to the outlet conduits.

In testimony whereof I affix my signature.

WILLIAM J. McCAIN.
